CONCEALED RADIATOR

Lawrence P. Dwyer, Winnetka, Ill., assignor to
 C. A. Dunham Company, Marshalltown, Iowa,
 a corporation of Iowa

Application June 12, 1931, Serial No. 543,871

4 Claims. (Cl. 237—79)

This invention relates to certain new and useful improvements in concealed radiators for heating systems, particularly steam or vapor heating systems, and relates to an improved assembly 5 adapted to be installed as a unit within the building wall and comprising a casing having an inlet and an outlet for the air to be heated, a radiator to be positioned within the casing, and the necessary appurtenances for controlling the heat output.

The importance of keeping all of the space in a building available for use, as well as the desire to avoid having heating equipment spoil the interior decorative effect or design, has made concealed 15 radiation very desirable. To accomplish this result the radiator is installed in a recess in the wall and delivers its heat principally by means of convection air currents, the air flowing into and through the recess and in contact with the radiator and being again discharged into the room after being heated. In view of the limited space 20 available within the wall, it is desirable to provide a heating unit having the greatest possible heating capacity in proportion to the space occupied thereby.

The present invention relates particularly to the casing in which the radiator is mounted and enclosed, and the inlet and outlet grilles for controlling the flow of air in contact with the 25 radiator. The radiating apparatus is adapted to be assembled at the factory and shipped and installed as a unit, provisions being made for adjusting the height of the casing to the wall space available and for mounting and securing 30 the casing within the wall, and for readily attaching the pipes of the heating system to the radiator.

The general object of this invention is to provide 35 an improved concealed radiator assembly such as briefly described hereinabove and disclosed more in detail in the specifications which follow.

Another object is to provide an improved casing or housing for the radiator which is adjustable for 40 use in wall recesses of different heights.

Another object is to provide an improved casing adapted to completely house the radiator and the traps and valves associated therewith, and adapted to permit the ready attachment of the 45 necessary piping.

Another object is to provide an improved concealed radiator and housing therefor adapted to be assembled and shipped as a unit and protected 50 against plaster, dirt and other building material after the radiator unit is installed and during the

time the building construction is being completed.

Another object is to provide improved means for mounting the inlet and outlet grilles on the housing after the radiator assembly has been installed in the wall.

Another object is to provide improved panels for enclosing the inlet and outlet openings during the shipment of the assembly and while the building construction is being completed (particularly the plastering operation), including means 10 for protecting the bolt-holes whereby the grilles are attached to prevent these holes from being filled with plaster.

Other objects and advantages of this invention will be more apparent from the following detailed description of certain approved forms of mechanism constructed according to the principles of this invention.

In the accompanying drawing:

Fig. 1 is a perspective view showing a portion 20 of the inside building wall with the radiator installed, the only portions of the apparatus visible in this view being the inlet and outlet grilles.

Fig. 2 is a similar perspective view showing the radiating units installed before the wall has 25 been completed by adding the lathing and plaster.

Fig. 3 is a sectional perspective view of the upper half of the casing.

Fig. 4 is a sectional perspective view of the 30 lower half of the casing.

The principal elements of this assembly include the casing or housing consisting of the upper casing section A and the lower casing section B, the upper outlet grille C and the lower 35 inlet grille D, and the heating mechanism housed within the casing. The assembly is fitted with the panels J and K while the assembly is being shipped and installed, and the grilles C and D are substituted for these panels after the assembly is installed and the building construction has been completed.

The casing members A and B are built up of suitable rather heavy sheet metal, the upper section A comprising a rear wall 1, end walls 2, and 40 a front wall 3, this casing section being open at the bottom but closed at the top by an upper wall 4. The width of the casing between the end walls 2 is sufficient to enclose all of the radiator parts, but is not too wide to be received within the recess between two of the upright studs 6 of the building frame. The depth of the casing between the rear wall 1 and front wall 3 is such that the casing can be completely received 45 within the recess between the inner and outer 50

55

sheathings of the wall, and preferably the dimensions of the entire housing are such that the rear and end walls thereof do not contact with the building members so that there will be 5 an insulating cushion of air surrounding all except the front side of the radiator assembly. If desired, a layer of heat insulating material may be positioned back of the rear wall of the casing. The upper portion of the front wall 3 is 10 cut away across the entire width of the casing to form an outlet opening for the heated air, this opening being surrounded by an outwardly projecting removable collar 7 having an outwardly extending flange 8 adapted to project through 15 the inner wall sheathing (the lathing and plaster) and enclose the outlet passage. The collar has vertically extending flanges 9 along its upper and lower edges which are removably attached to the casing member by means of screw bolts. 20 Similar flanges 10 at the ends of the collar are attached to outwardly projecting bracket plates 11 which in turn are adapted to be secured by means of nails or other suitable fastening means to the upright studs 6 of the building frame. By 25 making the collar 7 removable, it is possible to replace the collar with one of proper size in case an error is made in the dimensions of the grille to be attached thereto, without having to remove and replace the entire casing. A plurality of separate wires 13 are spot welded or otherwise secured at their central portions 14 to the front face of wall 3, the free end portions 15 of these wires being twisted about portions of the lathing and subsequently embedded in the plaster 30 11 whereby the casing section A is securely anchored in place with respect to the wall.

The lower casing section B has an upper portion of generally rectangular form but of slightly smaller dimensions than the lower portion of the 40 upper section A whereby the sections A and B may be telescoped over one another. The upper end of casing B is open as indicated at 18, the edges of this open end being surrounded by small inturned flanges 19 adapted to facilitate the telescoping of section B within section A. The lower end of section B is closed by a bottom plate 20 having downturned flanges 21 adapted to be suitably attached to the side and end walls of the casing whereby bottom plate 20 will be elevated 45 above the supporting beams of the frame structure so as to provide an insulating air space beneath the casing. The lower portion of the front wall 24 of casing B is cut away so as to provide an inlet opening extending across the entire 50 width of the chamber, and a collar 25 (generally similar to the collar 7 on section A) is secured about this inlet opening. This collar 25 has upper and lower vertically extending flanges 26 and 27 adapted to be removably secured to the section 55 B, and end flanges 28 adapted to be secured to the bracket plates 29 which in turn are nailed or otherwise anchored at 30 to the studs 6. The outwardly extending flange 31 of collar 25 which surrounds the inlet air opening is somewhat 60 longer than the flange 8 of the upper collar 7 since this lower collar not only extends through the lathing 16 and plaster 17 but also through the molding or baseboard 32. Openings 33 are cut through the end walls of the collar 25 and casing B to permit the insertion of the inlet pipe 34 and the outlet pipe 35 whereby connections are 65 made between the heating system and the radiator within the casing. The bottom wall 20 may be provided with openings in case the inlet and outlet pipes 34 and 35 are to be led in through 70 75

the bottom of the casing instead of through the end walls.

After the heating unit is assembled for shipment, and while the unit is being installed and the building wall completed, the outlet and inlet openings for the air are closed by the removable panels J and K (see Fig. 2). These wooden panels are adapted to fit within the respective openings and are held in place by means of metal straps 37 secured at 38 to the outer faces of the panels and 10 having projecting ends 39 through which are passed rather long screw bolts 40 engaged at their inner ends in threaded openings formed through the flanges 9, 26, and 27 of the collar and in reinforcing strips 41 secured against the opposite 15 faces of the casing walls. After the plastering 17 of the wall has been completed, the bolts 40 are withdrawn and the panels J and K removed.

The grilles C and D are each provided with an inwardly extending collar portion or flange adapted to fit within the respective collars 7 and 25 which enclose the outlet and inlet passages respectively, and each grille has an outwardly extending vertical flange portion 44 adapted to overlap the edges of the opening in the wall. 20 The grilles are secured in position by means of screw bolts 45 passed through suitable countersunk openings formed in the flanges 44 and engaged at their inner ends in the threaded holes formerly occupied by the bolts 40 which held the 30 panels J and K in position. It will be noted that these holes are occupied by the bolts 40 during the plastering operation whereby they will be kept open and clear for the reception of the grille bolts 45. The grilles C and D may be given 35 any suitable ornamental configuration on their outer surfaces and are provided with the slits or openings 46 to permit the free flow of air therethrough.

Suitable felt stripping is provided between the 40 flanges of grille C and the grille collar 7 to insure a tight joint and prevent injury to the adjacent portions of the building wall due to the possible leakage of heated air. If desired similar felt packing may be used around the lower grille D. 45 A suitable damper mounted behind the grille C is operated by knob 59.

It will now be apparent that this radiating apparatus can be assembled for the most part and shipped as a unit. The casing sections are installed in the wall recess, and by suitably adjusting the telescoping casing sections, the vertical distance between the air inlet and outlet openings can be adjusted within reasonable limits to fit the particular installation. Each casing section 55 is independently attached to the frame studding, the lower section being supported from the floor members, and the upper section being additionally supported by means of the inner wall sheathing. Insulating air spaces or spaces for other heat insulation are left around all of the walls of the casing except the front wall whereby heat losses are minimized. By making the grille-receiving collars 7 and 25 removable, these collars may be replaced in case the desired grilles do not 60 fit properly without necessitating the entire reconstruction of the casing member. When installed, the grille openings are temporarily closed by the panels J and K whereby the interior of the casing and the grille-receiving collars are 65 completely protected during the plastering and wall finishing operations, and also the screw holes whereby the grilles are eventually attached are protected against being filled with plaster by the temporary screw bolts 40 which attach the re- 70 75

movable panels in place. After the wall is completed these panels J and K are easily removed and the grilles C and D positioned over the openings. All parts of the apparatus are entirely concealed except the grilles which may be given any desired ornamental configuration to conform to the decorative scheme of the room. The radiator is easily removed and replaced when necessary by merely taking out the grille D. The pipe connections which connect the radiator with the heating system may be led in through either the end or bottom walls of the casing as may be most convenient.

I claim:

1. A metallic casing for enclosing a concealed radiator, said casing being adapted to be positioned within a building wall and provided in its front face with a lower inlet opening and an upper outlet opening, the casing comprising a plurality of telescoping sections, and wires secured to the front wall of the casing and adapted to be engaged with the lathing of the building structure and embedded within the plaster wall.

2. A metallic casing for enclosing a concealed radiator, said casing being adapted to be mounted within a building wall and provided in its front face with a lower air inlet opening and an upper outlet opening, and collars surrounding the openings and comprising a flange portion adapted to project through the inner sheathing of the build-

ing wall and inner laterally projecting flanges removably attached to the casing.

3. A metallic casing for enclosing a concealed radiator, said casing being adapted to be mounted within a building wall and provided in its front face with a lower air inlet opening and an upper outlet opening, collars surrounding the openings and comprising a flange portion adapted to project through the inner sheathing of the building wall and inner laterally projecting flanges removably attached to the casing, and grilles adapted to be removably attached over the openings and having portions adapted to fit within the collars.

4. In combination with a concealed radiator, 15 a metallic casing in which the radiator is mounted, said casing adapted to be positioned within a building wall and provided in its front face with a lower inlet opening and an upper outlet opening, there being outstanding flanges 20 at the sides of the openings, said flanges being formed with threaded holes for receiving screw bolts by means of which grilles are secured to the casing when the casing is installed within the wall, panels for temporarily covering the inlet 25 and outlet openings while the assembly is being shipped or installed, metal straps secured across the panels, and screw bolts extending through the straps and engaged in the threaded holes in the flanges.
